UNITED STATES PATENT OFFICE

NELS T. NELSON, OF ATTLEBORO, MASSACHUSETTS, ASSIGNOR TO J. F. STURDY'S SONS CO., OF ATTLEBORO FALLS, MASSACHUSETTS, A CORPORATION OF MASSACHUSETTS

CLASP

Application filed July 8, 1929. Serial No. 376,697.

This invention relates to a clasp for band bracelet or the like of the type worn for securing a watch on the wrist of the wearer and has for its object to provide a sheet metal 5 solderless construction with an imperforate top plate which may be embellished in any manner to form a suitable design.

A further object of this invention is the provision of a releasable clasp between two 10 sheet metal members which has gripping engagement at two widely placed points in order to more firmly hold it in position.

A still further object of this invention is the formation of sheet metal detents positioned to receive the tension of the strap and to better resist flexing or bending.

With these and other objects in view, the invention consists of certain novel features of construction, as will be more fully described, and particularly pointed out in the appended claim.

In the accompanying drawings:

Fig. 1 is a top plan view of the clasp with a portion of the ribbon band attached thereto.

Fig. 2 is a top plan view of one of the members of the clasp and showing the bottom of the other member of the clasp the members being detached and the ribbon lifted to expose these portions.

Fig. 3 is a perspective view of the stud member of the clasp with a portion of the ribbon band attached thereto.

Fig. 4 is a perspective view of the other or socket member of the clasp.

Fig. 5 is a sectional view on line 5—5 of Fig. 1.

Fig. 6 is a sectional view of Fig. 1 taken at right angles to the section of Fig. 5.

It is found of advantage to provide a clasp 40 for a ribbon bracelet which will have a top plate unhampered by a pierced design which is often necessary where portions of the top plate are used for attachment purposes. And it is also desirable to provide such constructions entirely of sheet stock to avoid soldering operations and in order to accomplish these desirable results I have provided exten-

45 sions at the sides of the sheet metal plate and folded these extensions back upon the 50 plate and then rolled them outwardly to form

detents, and I have also formed the opposite member with cooperating portions for engagement with these detents to releasably hold the parts together and the following is a detailed description of the present embodiment of this invention illustrating the preferred means by which these advantageous results may be accomplished.

With reference to the drawings 10 designates the stud member and 11 the socket member of this ribbon clasp. The stud member is blanked from sheet stock with side extensions 12 which are folded beneath the plate as illustrated in Figs. 3 and 5 and thence rolled outwardly as at 13 to form resilient 55 detents to snap beneath inturned portions of the flanges of the opposite member which will be presently described. The member 10 is also provided with a slot 14 through which the end 15 of the ribbon band may be looped 60 as at 16 and sewed in position.

The socket member 11 is a sheet metal construction upon which side flanges 17 are formed by folding a portion of the stock at either side thereof as illustrated in Fig. 4. 75 A portion 18 of the side flanges between slits 19 and 20 is bent inwardly to resiliently snap over the detents 13 of the stud member as will be apparent in Fig. 5.

Slots 21 and 22 are formed in the socket 80 member by cutting and folding portions of the stock 23 into a position at right angles to the base 24 of the socket as illustrated in the perspective view Fig. 4. Each portion is folded to abut the edge of the inturned 85 portion 18 as a stop which assists in aligning the braces 23 in manufacture. The portions 23 serve a triple purpose; they form the

slots 21 and 22 through which the ribbon 25 90 may be woven as illustrated in Fig. 6, to secure the socket member of the clasp in position. These portions 23 also brace the flanges 17 and prevents them from being collapsed inwardly. The portions also serve 95 to engage the edges 29 of the detents 13 to resist a tension or pull on the ribbon band.

It will be understood that when the ribbon 25 100 is under tension there will be sufficient friction to prevent the socket member from

sliding along the ribbon 25 and thus the same will be held in position in use.

The stud member 10 presents a broad surface 27 which may be embellished or ornamented as desired by a suitable design such as illustrated at 28 in Fig. 1 without the interruption of openings or the like which have often been objectionable in a clasp of this character. Also, the detents 13 by presenting their edges to the pull of the strap present their maximum resistance without liability of distortion.

The foregoing description is directed solely towards the construction illustrated, but I desire it to be understood that I reserve the privilege of resorting to all the mechanical changes to which the device is susceptible, the invention being defined and limited only by the terms of the appended claim.

20 I claim:

A clasp for a band bracelet or the like comprising a pair of superimposed sheet metal members one member having spaced transverse openings to slidably position it on a ribbon band and the other having an opening through which an end of the band may be looped, integral side extensions on one member folded toward each other and thence outwardly rolled to form resilient detents presenting their edges to the tension on the band, and side flanges on the other member having inturned portions to engage said detents and releasably hold said members in engagement, said flanges being braced by spaced cut and folded up portions of the stock of said member to engage their inner surfaces and also engage the edges of said detents and at the same time to form the above said spaced transverse openings for said ribbon band.

25 In testimony whereof I affix my signature.
NELS T. NELSON.
